US0D1089277S

(12) United States Design Patent (10) Patent No.: US D1,089,277 S
Bieter et al. (45) Date of Patent:  Aug. 19, 2025

- (54) DISPLAY SCREEN OR PORTION THEREOF WITH GRAPHICAL USER INTERFACE

(71) Applicant: Thomson Reuters Enterprises Centre GmbH, Zug (CH)

(72) Inventors: Nicholas Bieter, Saint Paul, MN (US); Brittany Shada, Farmington, MN (US); Chris Moellering, Farmington, MN (US); Jeff Arvidson, Eagan, MN (US); Doug Wozniak, Eagan, MN (US)

(73) Assignee: Thomson Reuters Enterprise Centre GmbH, Zug (CH)

() Term: 15 Years

(21) Appl. No.: 29/862,546

(22) Filed: Dec. 9, 2022

CLAIM

The ornamental design for a display screen or portion thereof with graphical user interface as shown and described.

DESCRIPTION

The sole FIGURE is a front view of a display screen or portion thereof with graphical user interface showing our new design.

The outermost broken line showing of the display screen or portion thereof and the broken line showing of the remainder of the graphical user interface is for environmental purposes only and forms no part of the claimed design.

1 Claim, 1 Drawing Sheet
